FIG-2.

UNITED STATES PATENT OFFICE

RUDOLPH REDLICH, JR., OF CHICAGO, ILLINOIS

DESIGN FOR A TABLE OR SIMILAR ARTICLE

Application filed January 9, 1933. Serial No. 46,768. Term of patent 7 years.

To all whom it may concern:

Be it known that I, RUDOLPH REDLICH, JR., a citizen of the United States, and a resident of the city of Chicago, county of Cook, and State of Illinois, have invented a new, original, and ornamental Design for a Table or Similar Article, of which the following is a specification, reference being had to the accompanying drawing, forming a part thereof.

In the drawing:

I claim:

The ornamental design for a table or a similar article, as shown.

RUDOLPH REDLICH, JR.
